Primary Examiner — Samantha Wood

(57) **CLAIM**

The ornamental design for a comfort control unit with thermostat, as shown and described.

DESCRIPTION

- 1.1 : Perspective
- 1.2 : Front
- 1.3 : Back
- 1.4 : Top
- 1.5 : Bottom
- 1.6 : Right
- 1.7 : Left
- 2.1 : Perspective
- 2.2 : Front
- 2.3 : Back
- 2.4 : Top
- 2.5 : Bottom
- 2.6 : Right
- 2.7 : Left

Portions of the drawings shown in broken lines form no part of the claimed design.

1 Claim, 14 Drawing Sheets(56)
